INDUCTION HEATER

James L. Adams, Jr., Youngstown, Ohio, assignor
to The Youngstown Sheet & Tube Company,
Youngstown, Ohio, a corporation of Ohio

Application November 16, 1928, Serial No. 319,800

11 Claims. (Cl. 219—13)

My invention relates to electric induction heaters, and more particularly to an induction heater for metallic shapes of substantially tubular or substantially continuous peripheral contour, 5 although the utility of the invention is not limited in this respect.

In heating the ends of tubular metallic shapes such as pipes, columns and other hollow bodies, preparatory to shaping the ends thereof for forming bells, collars, flanges, and the like, it has heretofore been customary to use gas or oil flames. The use of such flames for this purpose has been accompanied by considerable losses in 10 time and thermal energy. The use of a gas flame requires a continuously moving column of gases heated to the same temperature as the end of the shape in order to remove the products of combustion from around the ends of the shape, and the heat carried away by such a moving 15 column of gases is wasted. Such a flame also heats the metal comparatively slowly so that the radiation and conduction from the heated portion of the shape takes place for a relatively long time. It is also difficult to concentrate the heat 20 from such a flame over a definite area, and it is likewise difficult to obtain uniform heating throughout any substantial area of a given object, or uniformity in successive objects.

I provide an electric induction heater for metal shapes, the heater being of such construction that a portion of the shape to be heated is adapted to be included within a magnetic circuit in such manner that the metal of the shape constitutes either a closed or an open secondary circuit, depending upon the characteristics of the shape. The area of the shape which is heated is subject to exact control by the extent to which it is included within the magnetic circuit of the heater.

By concentrating magnetic lines of force in 40 such area, the metal composing the same is rapidly heated without the heat losses incident to combustion heating. In actual practice it has been found that from one-eighth ($\frac{1}{8}$ th) to one-twelfth ($\frac{1}{12}$ th) as much time is required for 45 the heating of an article in accordance with the present invention as that required for the heating of the same article to a corresponding temperature by combustion. By reason of this difference in time alone, it will be apparent that 50 heat losses due both to radiation and conduction are materially reduced. At the same time, the distribution of heat throughout the entire area is subject to accurate control so that uniform temperature conditions, or differential temperature conditions at will, may be obtained through-

out any given portion of the article, as will be hereinafter more fully set forth.

My invention also lends itself to an accurate control and timing of the energy input to successive articles, whereby uniform temperature conditions in corresponding parts of successive articles are insured. This permits such articles to be shaped under uniform temperature conditions and insures retention of this uniformity after cooling. By the use of the combustion 10 method of heating, there has been such a non-uniformity of heating that although successive shapes were subjected to similar shaping operations at the temperatures to which they were supplied to the shaping apparatus, they assume 15 different conditions upon cooling due to difference in the initial temperatures therein.

The present invention also possesses inherent advantages over the heating by combustion in that oxidation and scale formations are functions not only of the duration of the heating period but of the characteristics of the heating atmosphere. By the use of an induction heater, the period of heating is reduced and the article is subjected to atmospheric conditions less conducive to the formation of scale.

It will also be apparent to those skilled in the art that an induction heater lends itself to enclosure within a suitable room or casing in such manner that the access of air currents to the 30 article during the heating period may be reduced to a minimum or entirely eliminated.

In order to insure the desired concentration of energy in predetermined portions of an article undergoing treatment, I provide a magnetic circuit preferably including only a single air gap and substantially embracing a primary coil to which operative access is had through the gap. I also preferably construct the gap so that it substantially conforms both to the inside and outside contour of the article being heated, and so form the coil as to impart similar characteristics thereto. The invention contemplates, however, the possibility of so shaping the coil as to affect the control of the thermal energy input in different portions of a single article. By reason of the tremendous energy concentration herein contemplated, I provide cooling means preferably interlocked with the electrical circuit in such manner that cooling is automatically accomplished concomitantly with each heating operation.

In the accompanying drawings I have shown for purposes of illustration only, and not by way of limitation, certain preferred embodiments of the present invention, it being understood that 55

changes in the construction and operation therein illustrated may be made without departing either from the spirit of the invention or the scope of my broader claims.

5 In the drawings:—

Figure 1 is a longitudinal sectional view, partly in elevation, of an induction heater constructed in accordance with the present invention;

Figure 2 is a front elevation of the heater of 10 Figure 1;

Figure 3 is a rear elevation of the heater of 15 Figure 1;

Figures 4 and 5 are detail sectional views of a portion of a primary coil of modified characteristics shown in operative relation to an article being heated, and

Figure 6 is a view similar to Figure 1 of a modified embodiment of the invention.

In carrying out the present invention there may 20 be provided an induction heater comprising a frame or yoke 2, herein illustrated as being of substantially E-shape, although other constructional shapes may be utilized if desired. The outer legs 4 and 5 of the frame cooperate with a 25 central leg 6 which leg serves as a core about which a coil 7 of wound copper straps or bars is mounted. The legs 4 and 5 are provided with transversely extending pole pieces 8 suitably secured to the legs, and shaped to provide an opening 9 in axial alignment with the leg 6. The size and configuration of the pole pieces 8 as well 30 as the size and configuration of the core 6 is initially determined by the size and contour of the article to be heated, the parts preferably being so related as to provide a polar air gap of as moderately short radial lengths as is consistent with 35 the expeditious insertion thereinto and the removal therefrom of the article to be heated, although the dimensions of this gap may be materially changed without departing from the advantages inherent in the present invention.

The core 6 is preferably formed by the building-up of individual lamina or plates 11 of different widths and securing them together in any 45 desired manner, as by bolts 12, suitably insulated therefrom, so that the finished structure provides approximately the contour required.

The air gap 9 thus formed is adapted to receive the end portion 13 of the article to be heated 50 as indicated in Figure 1, such article preferably being inserted a distance such that substantially all of the convolutions of the primary coil 7 are effective thereon. Inasmuch as the efficiency of a coil of the character herein illustrated increases 55 appreciably as it more closely approaches the outer periphery of the article being heated, I preferably so construct the coil as to lie as closely adjacent such article as is possible, preferably making allowance only for the variations in dimensions permitted by commercial tolerances.

Assuming for example, that a heater in accordance with the present invention is being utilized for the heating of soft steel pipe ends having an outside diameter of 12 $\frac{1}{4}$ inches and an inside diameter of 12 inches, and that the heating is to be effective over a zone approximately 6 inches wide in a direction axially of the pipe, and that such area is to be raised to a temperature of approximately 900 to 1000 degrees C., I may utilize either 65 a periodically varying direct current circuit or an alternating current circuit such as an 110 volt 60 cycle circuit, utilizing 700 k. w. initial capacity and 150 k. w. final capacity, giving a mean value of about 350 k. w.

75 Under such conditions the desired heating will

be effected in a period of from 30 to 40 seconds. It will be apparent to those skilled in the art that such conditions of operation contemplate an initial secondary current of the magnitude of 85,000 amperes or 45,000 mean value and it therefore becomes apparent that the question of the dimensions of the air gap between the interior of the primary coil 7 and the outside of the portion 13 of the article being heated is of extreme importance. If too great a cross magnetic leakage 10 takes place through such air gap, the k. w. input into the heater becomes too low unless the input voltage is correspondingly increased. In order to effect as great a k. w. input as possible, and also by reason of the great radiation temperatures 15 met with in the primary coil, the inner surfaces of the copper straps 7 are left bare. By reason of this construction it is possible to obtain the desired proximity between the primary coil and the secondary surface.

20 It will be noted that in Figure 1 of the drawings, the primary coil is illustrated as having each turn thereof laminated. In addition to this the outer surfaces of the turns are shown as being in heat conducting relationship to a cooling duct 14 25 of suitable non-magnetic material, such as copper. In a preferred embodiment, cooling fluids circulate through the cooling duct 14 externally of the turns 7, although it may be positioned internally of such turns, or the turns may be of 30 divided construction with the cooling duct intermediate the inner and outer surfaces.

A tube 15 of insulating material, such as mica, may be disposed around the outer surfaces of the duct 14 and within the legs 4 and 5 of 35 the frame 2. This tube is effective for supporting the duct 14, and may be in turn held in position by suitable straps or brackets 15', as illustrated in Figure 3.

One end of the duct is shown as connected by 40 a flexible hose 16 of non-conducting material, such as rubber, to a supply valve 17, having a control means 18 projecting therefrom. The other end of the duct 14 is connected to a ground 45 and to a discharge pipe 20, although it will be understood that the ground may be at a suitable mid point of the coil, and that the duct may be so constructed as to provide a plurality of portions having a parallel flow therethrough.

The coil is supplied with electrical energy by 50 conductors 21 and 22 connected through a switch, contactor or suitable circuit breaker 24 to a supply circuit 25. As before indicated, this supply circuit may comprise a suitable source either of alternating current or of proper periodically varying current, as may be desired. The conductor 22 also has a connection 26 to the ground 19.

The circuit interrupter 24, or its operative 60 equivalent, may be provided with an operating connection 27 extending between the same and the operating means 18. It may also be provided with a core 28 positioned to be operated upon by a solenoid 29 having the current thereto controlled by a rotating contactor drum 30. This drum is herein illustrated as driven by a worm wheel 31 from a worm 32 on the shaft 33, of a suitable motor 34.

70 The contactor drum 30 may be of such construction as to periodically close and open the solenoid circuit in any desired time periods. By reason of this construction, it will be apparent that when the solenoid circuit is energized, the core 28 will be moved upwardly against the action of the spring 35 and thereby effect a closing 75

of the circuit to the primary coil and an opening of the valve 17 by means of which the supply of cooling fluid is delivered to duct 14. This condition will continue for a predetermined time interval dependent upon the construction of the contactor drum, which will be effective after the desired length of time for opening the circuit to the solenoid and thereby breaking the circuit to the primary coil 7 and closing the valve 17, although it will be understood that the water or other cooling fluid may be continuously passed through the duct if desired. It will be understood that a suitable signal may be provided if desired for the purpose of indicating to the operator of the apparatus each time the circuit is broken and the heating completed, so that the heated article may be removed and a fresh article inserted preparatory to the following heating period.

20 The conducting segment on the drum 30 is tapered as shown in Figure 1. By swinging the relatively fixed contact finger engaging the segment, the duration of, and the time intervening between, successive periods of energization of the inducing coil may easily be varied.

In Figure 4 I have illustrated a portion of a coil 7' in operative relation to a portion of the article 13' to be heated. In this figure the coil is shown as having the central portion thereof so constructed as to provide a slightly greater distance between the coils thereof and the periphery of the article.

In Figure 5 there is illustrated a coil 7" in cooperative relation to a portion of an article 13", the coil in this embodiment of the invention being constructed in such manner that the end portions provide a slightly greater gap with respect to the article than does the central portion.

40 These figures are representative only of different forms which the primary coil may assume for controlling the exact heat distribution throughout any portion of the article being heated.

45 In Figure 6 I have shown a modification of the invention particularly adapted for use with large diameter pipe having greater wall thicknesses. An inner coil 36 is mounted on the core 37. An outer coil 38 is mounted within the legs 4 and 5 in substantially the same manner as the coil 7 shown in Figure 1. The inner coil is provided with cooling ducts 39, and cooling ducts 40 are formed on the coil 38. The outer surface of the coil 36 and the inner surface of the coil 38 are brought as near the surface of the pipe 13 as the manufacturing tolerances of the pipe permits. The core 37 is provided with a pole piece 41 of approximately the same outer contour as the inner dimension of the pipe 13. By providing an inner and outer coil, it becomes possible to concentrate a greater amount of thermal energy in the pipe in a given space than is possible by the use of either coil alone. The operation of this form of the invention is substantially the same as that shown in Figure 1, and the circuit connections shown in Figure 1 are also applicable to this form of the invention.

While in the form of my invention illustrated in Figure 6 I have shown the cooling ducts 39 and 40 positioned inside and outside of the respective coils with which they cooperate in order to permit the coils to assume a position as close to the article being heated as possible, it will be apparent that operating conditions may dictate the necessity of utilizing cooling ducts otherwise disposed.

depending upon the exact construction of the coils utilized. In this respect, therefore, the figure of the drawings is illustrative only of one form of construction which may be utilized in carrying out my invention.

Certain advantages of the present invention arise from the provision of an induction heater by means of which the energy input may be concentrated throughout a given area so as to produce either uniform heating throughout that area or differential heating of different portions of the area.

Other advantages of the invention arise from the provision of an induction heater of the character referred to in which cooling means is provided in such manner as to permit the concentrated heating action desired without danger of injury to the apparatus.

Further advantages of the invention arise from the provision of an induction heater in which the cross-magnetic leakage is reduced to a minimum, thereby insuring a high operating efficiency and in which access to the heating zone is obtained through a single air gap of constant cross-sectional characteristics.

Still other advantages of the invention arise from the provision of a heating apparatus in which the cooling of the coil or coils may be correlated to the flow of current therethrough in such manner as to prevent the passage of current through the coil or coils without bringing the cooling means into operation.

Still other advantages of the invention arise from the provision of an induction heater in which there is a magnetic circuit including a single air gap with a coil, or plurality of coils, within said circuit and substantially embraced thereby in such manner that operative access to the coil or coils is had by inserting the article to be heated through such gap.

40 I claim:

1. In an electric induction pipe-end heater, an axially elongated, liquid-cooled inducing coil wound circumferentially with and very close to the surface contour of said pipe-end throughout the axial length of said coil so as to leave a very small air-occupied gap only therebetween, a substantially closed laminated magnetic circuit surrounding said coil on both inside and outside thereof except for a single narrow annular air gap in axial alignment with above mentioned air gap and giving free access to the inducing zone at all times by the pipe-end to be heated, means for supply of periodically variable current to said inducing coil, and means for accurately aligning said inducing coil axially with said annular air gap.

2. In an electric induction pipe-end heater, a liquid-cooled inducing means comprising two circumferentially wound but slightly radially spaced coil sections located respectively on inside and outside of said pipe-end and close to the respective surface contours of latter throughout the axial length of said coil sections, said sections being in substantially the same transverse plane with respect to pipe axis, a substantially closed laminated magnetic circuit encircling said coil sections except for a single narrow annular and axially directed air gap aligned axially with the narrow annular air-space between said coil sections, and means for supplying periodically variable current to said coil sections, said narrow magnetic air gap being freely accessible at all times to said pipe-end without structural changes.

3. In an electric induction pipe-end heater, an

- axially elongated and radially shallow water-cooled inducing coil wound circumferentially with and very close throughout to the surface contour of the pipe-end to be heated so as to give 5 very low magnetic leakage, a very narrow annular air gap in an otherwise substantially closed laminated magnetic circuit surrounding said coil on both inside and outside thereof, said air gap supplying free access at all times to said pipe-end 10 without shifting of parts, means for supplying periodically variable current to said coil, means for determinately graduating the point-to-point temperatures attained along said pipe-end, and means for timing successive heating periods.
- 15 4. In an electric induction pipe-end heater, two axially elongated and radially shallow water-cooled inducing coils wound concentric with each other and peripherally with the pipe-end to be heated but radially spaced very slightly in the 20 same plane transverse to pipe axis so as to provide free access of said pipe-end therebetween, a laminated magnetic circuit substantially enclosing said coils except for a single narrow annular pipe-guiding air gap therein axially aligned 25 with the annular space between coils and providing free access at all times to said pipe-end, means for supplying periodically variable current to said coils, means for determinately grading the heating back from the pipe-end as desired, and means 30 for determining equal energy supply to successive heats.
5. In an electric induction pipe-end heater, a liquid-cooled inducing means comprising two circumferentially wound but slightly radially spaced 35 coil sections adapted to receive a pipe-end therebetween and close to the respective surface contours thereof throughout the axial length of said coil sections, means for effecting the shading off of the heating back from the extreme pipe end, 40 and means for supplying periodically variable current to said coil sections.
- 45 6. In an electric induction pipe-end heater, a pair of inducing coils relatively elongated axially and lying substantially in one common radial plane but spaced apart very slightly to just permit the free entrance at all times of a pipe-end to be heated, a laminated magnetic circuit substantially enclosing said coils except for one narrow circular air-gap through which said pipe 50 end at all times has free access to its position between said coils, a laminated core inside the inner coil, said core being supported in alignment with said air-gap and completing the interior portion of said magnetic circuit, and a 55 source of periodically varying current connected
- to both of said coils so as to cumulatively excite said magnetic circuit.
7. In an induction heater, an inducing coil wound so as to lie peripherally very close to a tubular work-piece to be heated, a laminated magnetic circuit substantially enclosing said coil all around except for a shallow circular air-gap providing free access of said work-piece at all times to an operative inductive position closely adjacent to said coil surface, and means for supplying periodically variable current to said coil, the latter being characterized by a predetermined variation in the clearance distances of the several turns to the work-piece, for local regulation of the temperatures attained therealong. 5
8. In an electric induction heater, a primary inducing coil adapted to receive a work-piece to be heated, a substantially closed magnetic circuit embracing said coil, said circuit having an air-gap permitting introduction of the work-piece, 10 means for connecting said coil to a source of periodically varying current, means for operating said connecting means at predetermined time intervals, and means for adjusting the time interval between successive operations of said operating means. 15
9. In an electric induction heater, a primary inducing coil, means for supplying periodically varying current thereto, said coil being adapted to receive a work-piece, and an adjustable timing mechanism for periodically rendering said current supply means effective. 20
10. In an electric induction pipe-end heater, a relatively elongated primary inducing coil, means for connecting a source of periodically varying current to said coil, a substantially closed magnetic circuit embracing said coil and having an air-gap adapted to receive a work-piece to be heated, means for periodically operating said connecting means, said operating means including 25 means for varying the length of time during which the connecting means are operated. 30
11. In an electric induction pipe-end heater, two relatively elongated, co-axial primary inducing coils, said coils being adapted to receive an annular work-piece therebetween, a magnetic circuit embracing the coils, and an annular air-gap in the circuit adapted to receive the work-piece, 35 said coils being so connected to a common source of periodically varying current as substantially to minimize magnetic leakage between the coils when the work-piece is not disposed therebetween, by opposing their magnetizing forces in the intervening space. 40

JAMES L. ADAMS, JR.

55
